LOOM AND METHOD OF WEAVING

Frank J. MacDonald, Brookline, Mass., assignor
to Hood Rubber Company, Inc., Watertown,
Mass., a corporation of Delaware

Application May 13, 1938, Serial No. 207,724

14 Claims. (Cl. 139—11)

This invention relates to looms for weaving textile materials and to methods of weaving and articles produced thereby. The invention is especially useful in the production of formed articles, especially those having three dimensional characteristics, such as gloves, shoes and others of complex shapes.

Chief objects are to provide a loom for weaving such articles with a minimum of required trimming of the article, and therefore with a minimum of waste, and to provide for weaving the article directly to shape, even though it be of complex contour, as in the case of a footwear upper, for example, and with a minimum of subsequent sewing operations.

A more specific object is to provide for the elimination of wind-up or other mechanism which heretofore has had the disadvantage of so tensioning the woven fabric that the operation has been limited to the weaving of flat fabric. Accordingly it is an object to provide such freedom of the woven material that articles of complex contour may be woven with facility.

These and other objects will appear from the following description, and the accompanying drawings.

Of the drawings:

Fig. 1 is an end elevation of a loom embodying the apparatus of the invention in its preferred form, parts being broken away.

Fig. 2 is a plan view of the same parts being broken away, the warp supply mechanism being broken away.

Fig. 3 is a sectional elevation of the same taken on lines 3—3 of Fig. 2, parts being broken away.

Fig. 4 is a sectional elevation taken on line 4—4 of Fig. 2, parts being broken away.

Fig. 5 is a detail view of the selvage thread shuttle mechanism.

Fig. 6 is a sectional view taken on line 6—6 of Fig. 5.

Fig. 7 is a detail view showing selvage thread shuttle with the filler needle in its most advanced position with the filler threaded therethrough.

Fig. 8 is a detail side view of the shuttle.

Fig. 9 is a detail view of the selvage thread shuttle and the filler needle, illustrating how the filler is cast over the selvage thread shuttle at each pick.

Fig. 10 is a plan view of the shuttle showing the loop of filler being cast thereover.

Fig. 11 is a perspective detail view showing the heddle mechanism and the pattern cam, parts being broken away and parts shown in section.

Fig. 12 is a sectional elevation of the heddle mechanism, parts being broken away, the heddles being shown in one shed-forming position.

Fig. 13 is a similar view somewhat simplified by omission of parts, showing the heddles in a succeeding shed-forming position.

Fig. 14 is a view of two of the heddles to an enlarged scale, showing the partially completed fabric and illustrating the use of the heddles to beat up the filler.

Fig. 15 is a detail plan view of the operating ends of the heddles, the filler needle, and the partially completed fabric, the parts being shown in position assumed by them as the needle advances a succeeding loop of filler.

Fig. 16 is a similar view with the selvage thread looped through the filler loop and the needle returning.

Fig. 17 is a similar view with the needle fully withdrawn.

Fig. 18 is a plan view of a piece of unfinished fabric of varying width leaving the heddles, and showing how the selvage thread may replace the filler in the margin of the woven material.

Fig. 19 is a developed diagram of the operating cams illustrating the cycle of movements.

Fig. 20 is a plan view of a pattern cam for producing a glove such as that illustrated in Fig. 23.

Fig. 21 is a plan view of a pattern cam for producing the shoe upper of Fig. 25.

Fig. 22 is a similar view of a pattern cam for producing the helical fabric of Fig. 27.

Fig. 23 is a plan view of a finished woven glove, the dot and dash lines indicating the division of the weaving operations.

Fig. 24 is a rear view of the same.

Fig. 25 is a perspective view of a finished shoe upper, the dot and dash lines indicating the division of the weaving operations.

Fig. 26 is a view of the opposite side of the shoe upper.

Fig. 27 is a perspective view of a helical strip of fabric woven according to the invention.

Referring to the drawings:

45 The numerals 10, 11 designate the side frame members of the loom on which a main cam shaft 12, an auxiliary cam shaft 13, and a countershaft 14, are rotatably mounted parallel to each other. An electric motor 15, supplied by electric current from any convenient source, has a pulley 16 which drives the countershaft 14 at a reduced speed through a pulley 17 fixed to shaft 14 and a belt 18. Countershaft 14 has a pulley 19 fixed thereto, which drives cam shaft 12 at a reduced speed by means of a pulley 20, fixed thereto, and

a belt 21. Auxiliary cam shaft 13 is driven at half the speed of cam shaft 12 from that shaft by a sprocket 22, fixed to the cam shaft, a sprocket 23 fixed to the auxiliary cam shaft and a chain 24.

The machine includes means for individually tensioning a series of warp threads and a series of individual heddles, one for each warp thread, which are operated in alternate groups to form a shed for receiving the filler thread and are also used to force the filler into place in the woven fabric without the use of the usual comb or beater mechanism.

Provision is made for eliminating the usual wind-up mechanism so that little or no tension need be applied to the largest part of the woven material and so that consequently the woven material will be free to adjust itself, which facilitates the weaving of complicated shapes.

To support the heddles an L-shaped bar 25 (see Fig. 12) is mounted across the machine and fixed to the frame members 10, 11. The bar is slotted vertically at regular intervals to receive a series of sheet metal partition plates 26 which are welded or otherwise affixed to the bar in the slots to define a series of stalls within which the heddles are guided. The heddles each comprise a thin sheet metal bar 27 having an aperture or heddle eye 28 at its upper extremity. The heddles are all pivoted on a rod 29 which extends through aligned partition plates 26. A rod 30 extends along the margins of the partitions and is affixed thereto to assist in holding them in proper spaced relation and also acts as a stop to limit rotative movement of the heddles about the pivot rod 29. The lower ends of the heddles, below the pivot rod 29 are shorter and of less weight than their upper ends and the heddles are at all times inclined to the vertical so that they naturally lie in lowered position. Their lower ends are tapered on one edge at an acute angle to their length so as to provide substantial vertical pushing faces 31 to receive pressure to tilt the heddles to raised position.

The heddle pushing or shedding mechanism includes a pusher carriage 32 slidably mounted on the machine frame members 10, 11 for motion lengthwise of the machine toward and from the heddles. The carriage is actuated by a cam 33 fixed to cam shaft 12 and engaging rollers 34, 35 mounted on a sliding carriage 36. Levers 37, 37a are pivoted on the frame members 10, 11 by rod 38. Their upper extremities are pivotally attached to the carriage 32 at 39, 39a and they are engaged therebetween by the carriage 36 to which they are pivoted at 40. Carriage 32 supports a bar 41 extending cross-wise of the loom and channeled on its under side, as at 42.

Slidably supported on one end by the bar 25, and supported at the other end as hereinafter explained, and located under each heddle is a heddle-pusher 43, there being one for each heddle. Each heddle pusher comprises a thin strip of sheet metal formed at its heddle engaging end with a heddle lowering surface 44 and a heddle pushing surface 45 separated by a clearance notch 46, and at its opposite end with a raised projection 47 adapted to be engaged by a shoulder of the bar 41 defining the groove 42 to advance the heddle-pusher to elevate its heddle. Each heddle pusher is normally held with its projection 47 depressed so as not to be engaged by the bar 41 by a spring 48 mounted on a bar 49 fixed to the frame of the machine, there being one spring for each heddle pusher.

To provide for raising alternate heddles in groups, as in plain weaving, a swinging lift pin guide 50 is pivoted at 51, 52 to the frame of the loom by a rod 53. A cam 54 fixed to shaft 13 contacts a lever 55 which is pivoted to the frame of the loom at 56. A link 57 pivotally connects the upper end of the lever 55 to the lift pin guide at 58, the arrangement being such that the lift pin guide swings in one direction and remains stationary during the insertion of one pick of filler, then swings in the opposite direction and remains stationary during the succeeding pick. The lift pin guide 50 has two parallel rows of holes for guiding a number of push pins 59. Each push pin is formed with a loop at its upper end which straddles the rod 53 and has its lower end extending through an aperture in the guide 50. Every alternate pin extends through a hole in the same row, the others extending through the remaining row. Each heddle pusher 43 rests on the looped portion of one push pin 59.

Below the push pin guide is a stationary bar 60 arranged crosswise of the loom. The bar 60 is formed with a single row of apertures, one for each heddle, in which contact pins 60a are mounted to slide vertically. A leaf spring 60b bears upon a contact pin and holds it in depressed position, there being an individual leaf spring for each contact pin. In the swinging movement of the push rod guide 50, one set of push rods 59 is aligned over contact pins 60a during one pick and the other set of push rods is aligned thereover during a succeeding pick, the arrangement being such that raising of all the contact pins will elevate every other heddle pusher during one pick so that such heddle pushers engage the groove in bar 41 and elevate alternate heddles, and during the next pick, the remaining push pins will be lifted, raising the remaining heddles.

To provide for selectively lifting the heddles in prearranged order whereby to control the shape of the woven article, a rectangular frame 61 is mounted on the frame members 10, 11 and comprises a pair of side members 62, 63, having racks 62a, 63a, slidably mounted thereon, and a cross member 64 is connected to said racks. A table 65 is pivoted at one end thereof on cross member 64. A pair of rollers 66, 67 are mounted in bearings, fixed to a bar 68 which is vertically moveable so as to rest upon a pair of similar cams 70, 71 fixed to cam drum 107 mounted on shaft 12. The bar 68 is fixed to a pair of arms pivoted at 69 to frame members 10 and 11. The arrangement is such that at each revolution of cam shaft 12 the table 65 is in raised position during 70 degrees of rotation of the cam shaft and is in lowered position during 260 degrees thereof. The movement of the table 65 is such that at no position does it contact the pins 60a which are spaced therefrom at such a distance that when a template 72 is fixed to the table, any of the pins 60a above the template will be raised when the table 65 is raised so as to lift the corresponding heddle pushers 43 to a position where they will engage the bar 41 in its forward movement, thereby raising the corresponding heddles.

The template 72 may be of any desired shape. To provide for advancing the table 65 step by step as the weaving progresses, and thereby to control the shed at each pick, a shaft 73 is mounted cross-wise of the loom and is rotatable in bearings fixed to the frame members 10, 11. Fixed to shaft 73 are a pair of pinions 74, 75,

adapted to engage the rack teeth on members 62a, 63a, and a ratchet wheel 76. A crank 71 is also fixed to the shaft and provides means for manually advancing or returning the table 65.

A ratchet lever 78 is pivoted on shaft 73 and carries a spring pressed pawl 78a which may be turned into a plurality of positions to feed the ratchet wheel 76 in either direction. The lever 78 receives a rocking motion from a cam 79 which engages a roller 80, mounted on a push rod 81 pivotedly attached to lever 78 between nuts 82, 83 engaging a threaded portion of the lever, whereby the radius of the pivoted connection may be adjusted to control the arc of feed. The arrangement is such that the table is fed the width of one pick just before the table is elevated to raised position, and by reversing the ratchet pawl, the table may be fed in a reverse direction.

The warp threads 85 are individually wound on spools 86 supported by a creel 87 and travel through guides 88, 89 over a series of parallel rods 90 to the weaving position where they are guided under a rod 91 which determines the extent of the shed. Between the rods 90, take-up weights 92 are hung, one on each warp thread 20 to apply a fixed tension to the thread and to eliminate slack therein. Each warp is passed from under the rod 91 through the eye 28 of its heddle. The arrangement is such that each warp is kept taut whether or not it is being woven into the fabric at the moment.

The filler thread is manipulated through the shed by a needle 100 which is manipulated as follows: Extending laterally from the loom frame is a wing frame 101, supporting a rail 102. A carriage 103 is slidably mounted thereon. A rail 104 is mounted on the machine frame parallel to rail 102. A carriage 105 slidably mounted on rail 104, carries a roller which engages in a groove 106 in a cam drum 107 fixed to shaft 12. By rotation of the drum, the carriage is caused to reciprocate along the rail 104. A shaft 108 is journaled in bearings formed on the rail 104 with its axis extending warp-wise. A pinion 109 and a rope drum 110 are fixed thereon. A pair of guide pulleys 111, 112 are rotatably mounted on the frame at opposite ends of the rail. A drive rope 113 extends twice around the drum 110 to which it is attached at one point, and extends around the guide pulleys 111, 112, to provide a free reach parallel to the rail 102, to which the carriage 103 is attached. A rack bar 114 is fixed to the carriage 105 and engages the pinion 109. The arrangement is such that rotation of cam drum 107 reciprocates carriage 103. The needle 100 is positioned to be driven back and forth through the shed, and is guided by grooved guide pulleys 115, 116 rotatably mounted on the machine frame. The weft or filler thread 117 is drawn from a supply spool 118 and then through a tension 119, and is threaded through an eye 120 near the point of the needle. At each pick, a loop of filler thread is passed through the shed, where it is engaged by a selvage thread as hereinafter explained, the needle returning to form a succeeding loop.

A plate 121 is rigidly mounted on the frame of the loom opposite to the needle operating mechanism and has an aperture 122 through which the point of the needle passes. A tubular bearing 123 is fixed to the center of the plate and a shaft 124 is rotatably mounted therein. Fixed to this shaft are a pinion 125 and a crank arm 126. A cam 127 fixed to shaft 12 actuates a lever arm 128 which is pivoted to the frame of the loom 75

at 129 and carries a roller 130 adapted to engage the cam. A rack bar 131 is pivotally connected to the end of lever 128, as at 132 and its rack teeth engage the pinion 125, a roller 133 being rotatably mounted on plate 121 to guide the rack and keep it engaged with the pinion. The arrangement is such that the arm 126 is rotated a full revolution in one direction and then a full revolution in the opposite direction.

A looper 134, comprising a substantially circular disc, having a notch 135 in its periphery defining a looper hook 136 is rotatably mounted between a set of grooved guide pulleys 137 with its center in alignment with shaft 124. The pulleys 137 are arranged in pairs to readily span the notch 135, and are rotatably supported by plate 121 in such a position that the periphery of the looper disc is substantially close to the needle 100. Mounted upon the looper disc is a bracket 138 which carries a bobbin shaft 139 in which a bobbin 140 of selvage thread is rotatably mounted. A tension brake 141 on the end of the bobbin shaft, bears against the bobbin to prevent overrun thereof. A guard 142 partially enclosed the bobbin and is fixed to the looper disc. Apertures 143 provide tension means and guides through which the thread may be withdrawn. Guide rolls 144, 145 are rotatably mounted on the looper disc and guard, respectively, to reduce friction on the thread. A guide 146, for the needle, is fixed to the frame of the loom. The arrangement is such that as the needle 100 reaches its most advanced position, the hook 136 of the looper picks up the filler thread 117, and drawing a loop 148 therefrom, casts it over the entire looper plate so as to entwine it about the selvage thread 149. The looper is driven by a pin 147 on the arm 126 which loosely fits in the notch 135, thereby permitting the loop to pass entirely over the looper. The cam 127 is made of such contour as momentarily to reverse the motion of the pin 147 at the end of the rotative movement of the looper and thereby to provide clearance for the thread between the pin and the notch 135. This is indicated in the cam diagram of Fig. 19. As the needle is withdrawn, a loop of the selvage thread is drawn through the guide 146 by the loop of filler thread about which it is entwined.

The reach of the filler thread between the tension 119 and the eye of the needle is kept under constant tension so as to draw the selvage thread into the weave. By increasing this tension the filler loop may be drawn tight enough to pull the selvage thread into the weave in the form of loops, as shown in Fig. 18. Such a construction has certain advantages in that accidental cutting of the selvage thread does not release the loop of filler thread and where a selvage thread of contrasting color is employed, a border of contrasting color may be woven in the fabric. To provide such tension on the filler thread, a weighted take-up 150 is located between a thread guide 151 and the tension 119, and the thread 117 is passed under a pulley 152 on the take up, and over a pulley 153 adjacent the thread guide 151. A convenient method of weighting the take up is by pressure applied thereto by compressed air. For this purpose, a cylinder 154 is fixed to the frame of the loom. A piston 155 slidably mounted therein is attached to a rod 156 which is fixed to the take up weight 150. The upper end of the cylinder is closed by a stuffing box 157, the lower end being open to the atmosphere. A pipe 158 connects the upper end of the

cylinder to a source of compressed air or other pressure fluid.

Due to the absence of any means for beaming or otherwise withdrawing the finished fabric, the fabric may proceed in any direction from the forming position. This is of advantage in weaving articles in which the weaving proceeds in different planes. Articles of complicated construction, such as the glove of Fig. 23, the shoe upper of Fig. 25, or the helical strip of Fig. 27 may be woven in a continuous operation by weaving successive adjoining areas thereof in succession with the warp threads extending continuously through adjacent areas in which the warps extend in different directions, and the filler thread being also continuous throughout adjacent sections. Due to the independent take-ups on the warp threads and the template control of the operation of the heddles, warps may be worked into one section, dropped during the weaving of a second and picked up during the weaving of a third section adjacent the first.

Figs. 20, 21 and 22 illustrate the forms of templates 72 which may be affixed to the table 65 to control the heddles in weaving the articles illustrated in Figs. 23, 25 and 27, respectively. In weaving the article of Fig. 23 which is a glove having overlapped fingers, a template such as that illustrated in Fig. 20 is attached to the table and fed through the loom in the direction indicated by the arrow. As the portion of the template marked 160 passes under the heddle raising mechanism, the loom starts at the wrist of the back of the glove and weaves up the back to the tip of the index finger, certain warps being dropped at 161 on line 161a of the glove, and others being dropped at 162 at line 162a of the glove. As the part 163 passes through the loom, the inside face of the index finger is woven. At line 164 of the template certain warps are dropped on line 164a of the glove while at line 165 certain warps dropped during the weaving of the back of the index finger are picked up and the back of the index finger is started against the last pick utilizing such warps. In similar manner weaving proceeds up the back of one finger, then down the front thereof, the portion 166 forming the back of the middle finger, the part 167, the front thereof, the part 168 forming the back of the fourth finger, the part 169 the front thereof, the part 170 forming the back of the little finger and the part 171 the front thereof. At line 172, corresponding to line 164a on the face of the glove, the warps comprising the fronts of all the fingers are picked up. At line 173 of the template, the remaining warps are picked up and others are dropped at 174. The inside of the thumb is woven and controlled by part 175. The outside of the thumb is then woven and controlled by part 176. At line 177, all the warps are picked up and the part 178 completes the glove by weaving to the wrist over the palm. Whenever the edges of the article are parallel to the warps, the front and back of the glove will not be united but may be sewed.

In weaving the helical article of Fig. 27 the template shown in Fig. 22 may be used. As the template is moved through the loom in the direction of the arrow, the number of heddles raised, and therefore the width of the fabric, increases from the point 180 of the template until the point 181 reaches the heddle lifting pins. Thereafter warps are dropped progressively until the point 182 of the template is included. A triangular sector of the fabric is now completed. A new sector

is then woven in similar manner on the same warps and due to the individual take-ups on the warps, the new sector is woven directly against the preceding one, the warps changing direction 5 at the margin of the first sector. Weaving may be continued in similar manner throughout any desired length of fabric.

In weaving the shoe upper of Fig. 25 the template of Fig. 21 is employed. As the template 10 moves through the loom in the direction of the arrow, the toe cap segment of the shoe marked 185 is woven with the warps extending lengthwise of the foot, by the part 185a of the template. Next the tongue 186 is woven by the part 186a 15 of the template. The vamp segment 187 is then woven against the toe cap segment by the part 187a of the template. The segments 188, 189, and 190 are then woven against each other in succession, by the parts 188a, 189a, 190a of the template 20 to form a strip which may be later doubled upon itself and sewed together to form a lacing wing of the shoe. The quarter segment 191 is woven thereagainst by the part 191a of the template. All of the warps employed in weaving the first 25 lacing wing and quarter segment are then dropped and warps for forming the second lacing wing are picked up, the second side of the vamp including the vamp segment 192 and the wing segments 193, 194 and 195 being woven against the toe cap segment by the parts 192a, 193a, 194a, and 195a of the template. The remaining quarter segment 196 is woven thereagainst by the part 196a of the template. The warps used in 30 constructing the second lacing wing and quarter segment are now dropped and the tab 197 is woven on the warps extending from the tongue, from which the tab may be cut later, by the part 197a of the template. As the tab is completed, the warps laterally thereof extending from the quarter segments, are picked up in succession, controlled by the part 198a of the template, and the heel segment 198 is woven against the quarter segments 191, 196, the warps extending vertically of the shoe and the weaving terminating in a 35 margin which may be turned under the sole and concealed by the heel of the finished shoe.

Other formed articles may be woven in similar manner by providing templates therefor. The templates may be changed without disturbing the 40 adjustment of the loom and without appreciable expenditure of time. The template supporting table may be fed in either direction and in some cases articles may be woven by feeding a template in one direction and then in the other 45 direction in succession to produce a single article.

I claim:

1. A loom comprising a plurality of heddles for shedding the warps, said heddles being mounted to cross one another in scissors fashion and being 50 effective to pack the wefts by contact of the heddles with the wefts at the fell of the fabric during such crossing, and means for passing the weft through the shed.

2. A loom comprising a plurality of warp-controlling heddles, each having oblique weft packing surfaces, said heddles being mounted to cross one another in scissors fashion, and means for controlling the movement of the heddles to form successive sheds, said heddles being effective to pack the wefts successively in the warps by contact of said surfaces with the wefts at the fell of the fabric.

3. A loom comprising a series of heddles each adapted to control a single warp, each heddle comprising a pivoted blade having a heddle eye

in its operating tip, a heddle pusher slidably mounted to engage each heddle, a pattern cam adapted to control the rise of the heddles, means for actuating a group of heddles in their rising movement, and means controlled by said pattern cam for bringing heddle pushers into the path of said actuating means.

4. A loom comprising a series of heddles each adapted to control a single warp, each heddle comprising a pivoted blade having a heddle eye in its operating tip, a plurality of heddle pushers slidably mounted one to engage each heddle, a pattern cam adapted to control the rise of the heddles, means for collectively actuating a group of heddles in their rising movement by pressure applied through said heddle pushers, means actuated by said pattern cam for selectively moving individual heddle pushers into the path of said actuating means, and means for alternately causing said pattern-cam actuated means to be inoperative as to the odd and even heddles in the set during succeeding heddle raising movements.

5. A loom comprising a plurality of heddles each comprising a blade pivoted for edgewise motion and having a single heddle eye at a position remote from its pivot, adjacent blades being mounted to swing past each other in scissors fashion in their shed forming movements, and weft beating surfaces on each blade inclined to their direction of motion and directly adjacent the heddle eye therethrough and operable at the fell of the fabric for directly engaging the lay and forcing it into proper position in the fabric simultaneous with the forming of the succeeding shed.

6. A loom comprising a plurality of independent warp manipulating heddles arranged in line across the loom and each having a warp guide for controlling warps, reciprocating actuator means for simultaneously operating a plurality of said heddles in their shed forming movements, a pattern template, means for advancing said template step by step between shedding operations, individual contact means between each heddle and said template and controlled by the position and shape of said template to position groups of heddles in said line for engagement by said actuator means, and means for successively disconnecting alternate heddles in said line from said contact means during successive shedding operations.

7. A loom comprising a plurality of independent warp manipulating heddles arranged in line across the loom and each having a warp guide and a beating surface directly adjacent thereto and operable at the fell of the fabric to position a weft, reciprocating actuator means for simultaneously operating a plurality of said heddles in their shed forming and beating movements, a pattern template, means for advancing said template step by step between shedding operations, individual contact means between each heddle and said template and controlled by the position and shape of said template to position groups of heddles in said line for engagement by said actuator means, and means for successively disconnecting alternate heddles in said line from said contact means during successive shedding operations.

8. A loom comprising a plurality of independent warp manipulating heddles arranged in line across the loom and each having a warp guide for controlling warps, reciprocating actuator means for simultaneously operating a plurality of said heddles in their shed forming movements, a

pattern template, means for advancing said template in either direction step by step between shedding operations for reversing the pattern in successive blocks of weaving, individual contact means between each heddle and said template and controlled by the position and shape of said template to position groups of heddles in said line for engagement by said actuator means, and means for successively disconnecting alternate heddles in said line from said contact means during successive shedding operations.

9. A loom comprising a plurality of independent warp manipulating heddles arranged in line across the loom and each having a warp guide for controlling warps, reciprocating actuator means for simultaneously operating a plurality of said heddles in their shed forming movements, a pattern template, means for advancing said template step by step between shedding operations, individual contact means between each heddle and said template and controlled by the position and shape of said template to position groups of heddles in said line for engagement by said actuator means, means for intermittently advancing said template into engagement with said contact means between its step by step movements and for withdrawing it from contact during such step by step movements, and means for successively disconnecting alternate heddles in said line from said contact means during successive shedding operations.

10. In a loom comprising shedding mechanism for manipulating warp threads, a needle for inserting a loop of filler yarn through a shed, and a looper for entwining a selavage yarn through successive loops of the weft yarn, means for rotating the looper through a complete revolution at each pick to cast the looper yarn through the loop of filler advanced by the needle, said rotating means comprising a driving pin loosely engaging a slot in the looper for driving purposes, and means to reverse the rotation of the looper at the end of its revolution a sufficient amount to provide clearance for the loop of filler to pass over said looper along said pin.

11. In a loom comprising shedding mechanism for manipulating warp threads, a needle for inserting loops of filler yarn through successive sheds of the warp from one margin thereof, and a looper for entwining a selavage yarn through said loops, means for tensioning the filler yarn, said means comprising a fluid pressure cylinder, a piston in said cylinder, a tension pulley attached to said piston and engaging a loop of the filler thread, and means for supplying pressure to said cylinder to maintain the loop of filler yarn under constant tension.

12. A loom comprising a support for a flat template, a plurality of vertically movable pusher pins adapted to be held in their upper positions by a flat template upon said support, a plurality of heddles pivoted for operation in scissors-fashion, and a plurality of heddle pushers positionable in operative condition by said pusher pins in the upper positions of the latter.

13. A loom for weaving a formed article, said loom comprising a plurality of single eye heddles each controlling a single warp and adapted to draw the warps about the picks without restricting the movement of the woven material beyond the shedding position, individual tensioning means for each warp, template means for controlling movements of the heddles in a desired program of shed forming operations, needle means for inserting a filler of successive picks in

the form of loops of weft material each extending through a single shed, and means for entwining a selvage thread with the successive loops of weft material as they are laid to secure them in place.

14. A loom for weaving a formed article, said loom comprising individual supply means for each warp, individual tension means for keeping each warp free from slack between its supply means and a shedding position, a plurality of heddles each having an eye adapted to guide a single warp at the shedding position and formed and arranged to manipulate said warps at such

positions to form a succession of sheds for receiving successive picks of filler material, and to draw said warps about the picks without restricting the movement of the woven material beyond the shedding position, shedding means adapted to actuate said heddles in consecutive similar movements of alternate heddles to form a succession of sheds, pattern means for modifying the shedding movements of individual heddles to control the shape of the article, and needle means for inserting loops of weft material between the warps of successive sheds.
